UNITED STATES PATENT OFFICE.

ARTHUR TREVOR DAWSON AND GEORGE THOMAS BUCKHAM, OF LONDON, ENGLAND, ASSIGNORS TO VICKERS, SONS & MAXIM, LIMITED, OF WESTMINSTER, ENGLAND.

AUTOMATIC OR OTHER MACHINE-GUN.

SPECIFICATION forming part of Letters Patent No. 687,130, dated November 19, 1901.

Application filed August 3, 1901. Serial No. 70,802. (No model.)

To all whom it may concern:

Be it known that we, ARTHUR TREVOR DAWSON, late lieutenant of Royal Navy, and GEORGE THOMAS BUCKHAM, engineer, subjects of the King of Great Britain, both residing at 32 Victoria street, Westminster, London, England, have invented certain new and useful Improvements in Automatic or other Machine-Guns, of which the following is a specification.

This invention has reference to automatic and other machine-guns, and is especially applicable to those having a sliding barrel and a water-jacket, as in the well-known Maxim thirty-seven-millimeter gun, the chief object of our invention being to so construct these guns that the barrel and its water-jacket can be readily and simultaneously detached for convenience in transporting the gun. For this purpose we form the breech end of the barrel with lateral fins or projections to engage with corresponding grooves or recesses in the recoiling plates or frame, and we also form the breech end of the water-jacket with dovetail or similar grooves for the reception of correspondingly-shaped ribs or projections on the breech-casing. The aforesaid grooves or recesses in the recoiling frame and the aforesaid dovetail grooves in the breech end of the water-jacket are preferably disposed vertically, so as to permit of the parts fitting together by a vertical movement. Obviously, if found advantageous, the position of the said grooves and projections relatively to each other may be reversed.

In order that our said invention may be clearly understood and readily carried into effect, we will proceed to describe the same more fully with reference to the accompanying drawings, in which—

Figure 1 is a side elevation, and Fig. 2 a plan, of a Maxim gun provided with our improvements, the detachable water-jacket and barrel being represented in these figures detached from the breech-casing. Fig. 3 is a side elevation of the gun with a portion broken away to show the said parts connected. In this view we have represented a lever or tool in position for facilitating the

detachment of the parts and with such detachment partly effected.

A are the side plates of the breech-casing, and B B the recoiling plates or frame.

C is the barrel, and D the water-jacket.

c c are the lateral fins or projections on the barrel, near the breech end thereof, and b b are the corresponding recesses or vertical grooves in the recoiling plates B, with which said fins or projections are adapted to engage. The metal at the entrance to these recesses or grooves is faced off, as shown in Fig. 2, and the lower ends of the projections c are curved or rounded, Fig. 1, so as to facilitate the engagement of the said projections with the said grooves.

d d are the vertical dovetailed recesses or grooves in the water-jacket, and a a the corresponding ribs or projections on the breech-casing, with which they are adapted to engage. The said dovetailed ribs a are located on the inner surface of the side plates A of the breech-casing and preferably consist of tapered strips riveted or otherwise securely connected to said side plates. At or near the bottom of the said side plates stops a' 75 may be provided for preventing the water-jacket and its barrel from descending too far when being connected with the breech-casing.

In order to connect the parts, it is necessary to first detach the hinged cover A' of the breech-casing by the removal of its hinge-pin a' and also to detach the feed-block E and the lock. The water-jacket, with its barrel, is then placed in such position relatively to the breech-casing that the dovetail strips a on the casing and the grooves b in the recoiling frame coincide with the dovetail recesses d in the water-jacket and the lateral fins or projections c on the barrel. The said water-jacket and barrel are then pressed downwardly with respect to the breech-casing and the upper portion of the barrel is given a slight blow to cause the parts to become firmly connected together, the aforesaid stops a' 95 limiting the extent of movement of the water-jacket and barrel in this operation. The cover, feed-block, and lock are then replaced

and a transverse pin a^2 is inserted to retain the connected parts together. The gun is then ready to be mounted on its tripod or support for firing.

5. F is the tool or lever which may be employed for facilitating the detachment of the barrel and water-jacket from the breech-casing. This tool or lever is constructed with a bent or curved front part f to engage with 10 the rear portion d' of the water-jacket, and it is also formed with a forked portion f' to bear upon the upper portion of each of the recoilings-plates or other convenient part of the breech-casing at points serving as a fulcrum 15 for the lever to turn about in starting the upward movement of the water-jacket and barrel with respect to the breech-casing. The parts having thus been initially liberated from engagement with one another their complete 20 detachment can readily be effected by the operator's hands without further use of the aforesaid tool.

We do not wish to confine ourselves to the specific means hereinbefore described for enabling the water-jacket and barrel to be disconnected from the breech-casing and recoilings frame of the gun, as any other appropriate means may be employed that will permit of simultaneous detachment and attachment 30 of these parts.

What we claim, and desire to secure by Letters Patent of the United States, is—

1. A machine-gun provided with means for enabling the barrel and water-jacket to be simultaneously connected to or detached from 35 the other parts of the gun for the purpose specified.

2. A machine-gun in which the barrel and water-jacket are temporarily connected to 40 the breech-casing side plates and the recoilings plates by projections and grooves formed respectively on and in the said parts and adapted to be simultaneously engaged and disengaged substantially as and for the purpose 45 specified.

3. In a machine-gun, the combination of projections on the breech-casing side plates adapted to engage with corresponding grooves in the water-jacket, and of projections on the 50 barrel adapted to engage with corresponding grooves in the recoil-plates substantially as and for the purpose specified.

4. In a machine-gun, the combination of lateral projections on the interior surface of 55 the breech-casing side plates adapted to engage with corresponding vertical grooves in the water-jacket, of lateral projections on the barrel adapted to engage with corresponding vertical grooves in the recoil-plates and of

means for limiting the extent to which the 60 parts can move in the assembling operation, substantially as described.

5. In a machine-gun, the combination of laterally-disposed vertical and tapered projections on the interior surface of the breech- 65 casing side plates adapted to engage with corresponding vertical grooves in the water-jacket, of laterally-disposed vertical projections on the barrel adapted to engage with corresponding grooves in the recoil-plates, of 70 stops on the side plates for limiting the extent to which the parts can move in the assembling operation and of means for locking the parts together when assembled substantially as described.

6. In a machine-gun, the combination of laterally-disposed vertical and tapered projections riveted to the interior surface of the breech-casing side plates and adapted to engage with corresponding vertical grooves in 80 the water-jacket, of laterally-disposed vertical projections on the barrel adapted to engage with corresponding grooves in the recoil-plates, of stops on the side plates for limiting the extent to which the parts can move 85 in the assembling operation, and of a pin passing through the rear portion of the water-jacket and engaging with the said side plates for locking the parts together when assembled substantially as described.

7. In a machine-gun, the combination of projections on the breech-casing side plates adapted to engage with corresponding grooves in the water-jacket, of projections on the barrel adapted to engage with corresponding 95 grooves in the recoil-plates and of means for facilitating the release of these parts when engaged substantially as described.

8. In a machine-gun, the combination of projections on the breech-casing side plates adapted to engage with corresponding grooves in the water-jacket, of projections on the barrel adapted to engage with corresponding grooves in the recoil-plates and of a lever having a curved outer end to engage with the 105 water-jacket and having a forked portion serving as a fulcrum where it bears upon the recoil-plates substantially as and for the purpose specified.

In testimony whereof we have hereunto set 110 our hands, in presence of two subscribing witnesses, this 19th day of July, 1901.

ARTHUR TREVOR DAWSON.
GEORGE THOMAS BUCKHAM.
